UNITED STATES PATENT OFFICE.

ARTHUR C. KEPPLER, OF SOUTH BEND, INDIANA.

SIGNALING DEVICE.

Application filed March 21, 1921. Serial No. 454,092.

To all whom it may concern:

Be it known that I, ARTHUR C. KEPPLER, a citizen of the United States, residing at South Bend, in the county of Saint Joseph and State of Indiana, have invented certain new and useful Improvements in Signaling Devices, of which the following is a specification, reference being had to the accompanying drawings.

10 This invention relates to signaling devices for automobiles, and more particularly to a device of the semaphore type adapted to give notice to pedestrians and traffic of the intention of the operator of the automobile to 15 which it is attached to alter his course or to stop.

An important object of the invention is to provide a device of this character embodying a shiftable semaphore arm which by its 20 shifting brings into view various signaling devices announcing the intention of the operator.

A further object of the invention is to provide an improved structure whereby the operation of the arm and the shifting of the 25 signaling devices is obtained.

Other objects and advantages of the invention will become apparent throughout the course of the following description.

30 In the accompanying drawings, wherein for the purpose of illustration is shown a preferred embodiment of my invention and wherein like reference characters designate like parts throughout:

35 Figure 1 is a side elevation of a signaling device constructed in accordance with my invention showing in dotted lines the various positions assumed by the arm and the signals displayed when the arm is in such positions;

40 Figure 2 is a sectional view showing the operating mechanism for the arm;

Figure 3 is a longitudinal sectional view taken through the arm;

45 Figure 4 is a section on the line 4—4 of Figure 3;

Figure 5 is a section on the line 5—5 of Figure 3;

Figure 6 is a side elevation of one of the 50 display strips employed;

Figure 7 is a plan view of the casing detached and

Figure 8 is a section on the line 8—8 of Figure 3.

55 Referring now more particularly to the drawings, the numeral 10 indicates a cylin-

drical casing, and the numeral 11 a band whereby the casing may be attached to the door of an automobile or other convenient mounting point. The casing 10 is provided with a reduced flattened extension 12 in which is pivoted for oscillation, an arm 14.

Rotatably mounted within the cylinder is an interiorly worm-threaded sleeve 15 embodying an operating handle 16 extending through a slot 17 formed in the casing 10, the slot being provided with regulating notches 18 so that the operating arm 16 may be retained in adjusted position. Mounted within the sleeve 15 is an exteriorly worm-threaded plunger 19 the threads of which engage with the threads of the sleeve 15, and this plunger is connected with the arm 14 at a point spaced from the pivot point 13 thereof longitudinally of the arm by a link 20, the connection of the link being such as to prevent rotation of the plunger 19.

It will be noted that the plunger 19, being held against rotation, if the sleeve 15 is rotated through medium of the handle 16 the plunger or piston 19 will be shifted longitudinally of the casing 10 and will cause the arm 14 to oscillate upon the pivot thereof, the degree of oscillation obtained being determined by the amount of rotation being imparted to the sleeve 15. The construction of the threads of the sleeve and piston 19 is preferably such that it requires but a rotation of the sleeve through 180° to shift the arm to its extreme position, so that a very slight shifting will suffice to obtain the desired adjusting of the arm.

The arm 14 embodies spaced walls 21, each provided adjacent the free end of the arm with a transparency covered opening 22. Intermediate the side walls 21 and more particularly intermediate the transparency openings 22 thereof, is arranged a hollow partition 23 in which is arranged an illuminating element 24 adapted to shine through the openings 22 of the side walls.

Within the arm at the free end thereof are mounted spools 25 and 26, each having rolled thereon an indicia bearing element 27 which is transparent, the ends of these elements being connected to a common operating wire 28 secured to the flattened extension 12 of the casing 10 at a point well spaced from the pivot point 13 of the arm 14. The spools 25 and 26 are of the automatic rewind type being provided centrally with a coil spring 29, one end of which is secured

to the arm 14 and the opposite end of which is secured to the spool. The indicia bearing elements 27 are provided with spaced indicia 30 which are preferably colored some 5 distinctive color.

The operating wire 28 of the indicia bearing elements 27, being secured to the casing extension 12 at a point spaced at the pivot point of the arm 14, the oscillation of the 10 arm 14 about its pivot will have the effect of causing the indicia bearing elements 27 to be shifted longitudinally of the arm so that when the arm reaches the lowermost 15 position the first of the indicia bearing elements is brought to view and the signal indicates, in accordance with the present showing, that the driver intends to turn to the left. Further oscillation of the arm to bring the same to a horizontal position causes further 20 shifting of the indicia bearing elements and at the horizontal position the signal indicates that the operator of the vehicle intends to stop. Similarly, when the arm is in the extreme elevated position the showing 25 indicates that he intends to turn to the right. Since two of the indicia bearing elements 27 are provided, one of which extends upon each side of the partition 23, the light shining from the illuminating element 24 30 within the partition will render these indicia visible both in front of and behind the vehicle, so that the operator's intention will be apparent not only to vehicles in the rear but to vehicles and pedestrians which the vehicle 35 to which the device is attached is approaching.

From the foregoing it is believed to be obvious that I have constructed an automobile signal which is particularly well 40 adapted for use by reason of the fact that it not only indicates the intention of the operator of the vehicle by the changed position of the arm, but by the changing of the visible indicia. It will furthermore be obvious 45 that the construction hereinbefore set forth is capable of some change and modification without departing from the spirit of my invention, and I accordingly do not limit myself to the specific structure hereinbefore set forth except as hereinafter 50 claimed.

What I claim is:

1. In an automobile signal, an arm mount-

ed for oscillation, means for oscillating said arm, indicia bearing elements mounted with- 55 in said arm and embodying longitudinally spaced indicia, alined openings formed in the side walls of said arm, and means operated by the oscillation of said arm for shifting said indicia bearing elements longitudinally 60 to aline the indicia thereof with said openings.

2. In an automobile signal, an arm pivoted at one end for oscillation, means for oscillating said arm, said arm embodying 65 side walls having alined openings formed therein adjacent the free end thereof, a longitudinally shiftable indicia bearing element mounted within said arm and embodying longitudinally spaced indicia, means operated by the oscillation of said arm in one direction for shifting said indicia bearing elements longitudinally to aline the indicia thereof with said openings, and means for automatically returning said indicia bearing 70 element to normal position upon the oscillation of the arm in the opposite direction.

3. In an automobile signal, a support, an arm embodying spaced side walls pivotally connected with said support, means for oscillating said arm, an automatic re-wind spool disposed within said arm at the free end thereof, an opening formed in the side wall of the arm and indicia bearing elements wound upon the spool and embodying longitudinally spaced indicia, and a connection 80 between said indicia bearing element and said support at a point spaced from the pivot point of said arm.

4. In an automobile signal, a support, an arm pivotally connected with the support and embodying spaced side walls having alined openings formed therein adjacent the end thereof, a partition disposed intermediate said arms, an illuminating element 90 mounted in the partition, a pair of automatic re-wind spools rotatably mounted in said arm at the free end thereof, indicia bearing elements wound upon said spools and extending to opposite sides of said partition, 95 and a connection between the ends of said indicia bearing element and said support.

In testimony whereof I hereunto affix my signature.

ARTHUR C. KEPPLER.
